UNITED STATES PATENT OFFICE.

WILLIAM C. DE ARMOND AND WILLIAM RAY H. WATT, OF PHILADELPHIA, PENNSYLVANIA.

COIN-CONTROLLED DEVICE.

Original application filed July 2, 1925, Serial No. 40,997. Divided and this application filed September 10, 1925. Serial No. 55,429.

Our invention relates to a novel and useful coin controlled device of the type disclosed in our copending application filed July 2, 1925, bearing the Serial #40,997 5 and it relates more particularly to a coin controlled device adapted to be used in conjunction with the mixed beverage dispensing apparatus disclosed and claimed in said copending application, though it is adapted 10 to be used as a coin controlling means for any machine or device, wherein it is desired to lock any operating handle, lever or shaft against any operation thereof, until a particular coin is deposited within a coin slot 15 in the novel coin controlled device.

Our invention further relates to a novel float controlling means in combination with such coin controlled device, whereby there is superimposed upon the coin controlled device an additional locking means governed 20 or actuated by the height of any liquid in any desired reservoir, so as to render inoperative the coin controlled device and hence, the machine or apparatus controlled 25 thereby, when the level of the liquid in such reservoir is below a predetermined low level.

With the above ends in view, our novel coin controlled device consists of a slide, 30 slidably mounted upon the back of the panel or wall of the cabinet or housing of the apparatus or machine which is to be controlled thereby, in such a manner that said slide will not be accessible from the outside of such housing, casing or cabinet. A suitable coin slot is provided in said slide, while a corresponding coin slot of suitable size is provided in such panel or wall of the cabinet or casing to coincide with said first coin 35 slot in the normal position of said slide. A pair of suitable inclined racks are provided parallel to said slide, while suitable means are provided upon said slide to interlock with one of said racks in the direction of the operating stroke of the slide. There is further provided a suitable coin retaining and position-means upon said slide to so position the coin inserted into said coin slot as to withdraw said interlocking means from 40 engagement with said rack and at the same time to interlock with said second rack in the direction of the return stroke of said slide, thereby permitting the movement of said slide through the operative stroke there-

of when a coin is inserted in said coin slot; 55 while locking said slide against the return movement until said slide has been moved through the complete operative stroke. Our invention further contemplates means carried by said slide for engaging a lever, handle or shaft, in such a manner that said handle, lever or shaft may be moved or displaced only with the operative movement of said slide, thereby to lock such handle, lever or shaft, and hence the machine or apparatus of which it forms an operative part, 60 against any operation thereof, until a coin of the predetermined denomination has been inserted into the coin slot of said coin controlled device. 70

Our invention further consists of novel float controlled locking means cooperating with the locking means in said slide and operatively interconnected with a suitable float in any desired reservoir, so as to prevent the withdrawal of such locking means 75 from the interlocking position with said rack when said float is below a given level.

For the purpose of illustrating our invention, we have shown in the accompanying drawings forms thereof which are at present preferred by us, since they will give in practice satisfactory and reliable results, although it is to be understood that the various instrumentalities of which our invention 80 consists may be variously arranged and organized and that our invention is not limited to the precise arrangement and organization 85 of these instrumentalities as herein shown and described. 90

Referring to the drawings:—

Figure 1 represents an elevational view of a novel coin controlled device embodying our invention.

Figure 2 represents a section on line 2—2 95 of Figure 1 on an enlarged scale.

Figure 3 represents a section on line 3—3 of Figure 1 on a similarly enlarged scale.

Figure 4 represents an elevational view similar to that shown in Figure 1, showing 100 a modified form of a float locking device embodying our invention.

Referring to the drawings, in which like reference characters indicate like parts, 105 1 designates the main shaft of a machine or apparatus to be controlled by our novel coin controlled device, having secured rigidly thereto an operating lever 2 having a handle

or knob 3, on the outer end thereof whereby said shaft 1, and hence, the apparatus of which it forms a part is operated or actuated. 4 designates the front panel or wall of a cabinet or casing containing the apparatus or machine to be controlled and is provided with an elongated slot or opening 5 in line with the movement of the lever 2, through which said lever extends and within which said lever may be moved to and fro. 6 and 7 designate two parallel guide members secured to the back of said panel or wall 4 parallel to the elongated opening 5 and on either side thereof. Between the two guides 6 and 7, is slidably mounted the slide 8, of suitable length, being provided with an opening 9 therethrough, through which, said operating lever may pass, in a manner shown particularly in Figures 1, 2 and 4. Thus, the lever 2 and the slide 8 will move in unison with each other.

The slide 8 is provided with a coin slot 10 at a right angle to its line of travel as shown particularly in Figures 1 and 2, while the panel 4 is provided with a similar coin slot 11, positioned so as to coincide with said coin slot 10 in the normal position of said slide 8, as shown particularly in Figure 2; said coin slot being of a size 30 to receive a coin of a particular denomination.

In order normally to lock the slide 8 against any downward or operative movement thereof, and hence, normally to lock the operating lever 2, there is provided a catch 12 having a locking ledge or nose 14 which is adapted to interlock in a downward direction with corresponding horizontal ledges 15 of the upwardly inclined teeth 16 of the stationary rack 17 secured to the guide member 6. The spring 18, pivotally mounted upon the pivot screw 13, is interposed between said catch 12 and the coin plate 19, also carried by said slide 8, in such a manner as constantly to urge said catch into interlocking engagement with the teeth of said rack 17.

The horizontal coin plate 19 is carried by the slide 8, in a manner shown particularly in Figures 2 and 3, by means of the upright portion 20 thereof, formed integral therewith. The coin plate is positioned directly above the coin slot 10, as shown in Figure 2; while a small coin bracket 21 is secured to the slide 8 directly beneath the coin slot 10, in such a manner as to lend support to the outer edge of the coin after it is fully inserted through said coin slot 10. The coin plate 19 is further provided at its further edge with a slight horizontal and overhanging nose piece or support 22 which is adapted to act as a stop for the coin as it is inserted through the coin slot 10 and also adapted to engage and support the innermost edge of said coin, thereby to retain

said coin in a horizontal position directly beneath the coin plate 19. The catch 12 is provided with the downwardly extending finger 23 which is adapted to oscillate to and fro in a slight recess 24 in the coin plate 19, adapted to receive such finger, said finger 23 extending downwardly below the coin plate 19 into operative alignment with the edge of the coin.

There is further provided a second upright rack secured to the guide 7 having a series of downwardly inclined teeth provided with the lower horizontal ledges 27. Thus, as the coin is inserted through the coin slots 11 and 10 into position beneath the coin plate 19, it encounters and engages the finger 23 and moves the same outwardly against the force of the spring 18, and thereby withdraws the locking ledge 14 of the catch 12 from locking engagement with the uppermost tooth of the rack 17. As the coin is fully inserted into the coin slot 10, however, the finger 23, urged by the force of the spring 18, moves said coin a slight distance to one side in the direction of the rack 25, thus forcing the edge of the said coin into locking engagement with one of the lower horizontal ledges 27 of one of the teeth 26 of said rack 25.

The coin thus inserted, having withdrawn the catch 12 from locking engagement with the rack 17, permits the downward operative movement of the slide 8 and hence, permits the operative movement of the actuating lever 2 carried by the operating shaft 1 of the machine or apparatus to be controlled by such coin. As the slide 8 is thus moved downwardly by the lever 2, the edge of the coin, carried beneath the coin plate 19, by the coin supports 21 and 22 and urged by the finger 23, successively engages each of the teeth 26 of the rack 25 in its downward travel, successively interlocking with each of the lower horizontal ledges 27 of such teeth, in such a manner as to prevent the upward or return movement of the slide 8 and hence, the operating lever 2. When

the slide 8 has been moved, by means of the operating lever 2, to the lower limit of its operative stroke, the edge of the coin will clear the lower end 28 of the rack 25 and hence will be discharged from beneath the coin plate 19 by said finger 23 into any suitable coin collecting receptacle, thus permitting the return movement of the slide 8 into the upper normal position. The discharge of the coin from beneath the coin plate 19 also permits the reengagement of the catch 12 with the teeth of the rack 17 as the slide 8 is moved upwardly, thus locking said slide 8 against the downward or operative movement until another coin is inserted through the coin slots 11 and 10.

In order to render the coin controlled apparatus inoperative and hence to lock the

handle 12 in the upper normal position when the level 29 of the liquid 30 in the reservoir 31 is below a predetermined lower limit, there is provided a float 32 carried by an upright rod 33 which is slidably mounted in the two guides 34 and 35. The rod 33 interconnects with a second upright rod 36 slidably mounted in the slides 37 and 38 by means of the upper horizontal connecting rod. The dog 40 is carried by the lower end of the rod 36 in such a position as to be lowered down between the edge 41 of the catch 12 and the edge 42 of the rack member 25 when the float 32 is lowered below the lower limit by the corresponding lowering of the level 29 of the liquid 30. The interposition of the dog between the catch 12 and the rack member 25 in such a manner, locks said catch 12 in its interlocking position shown in figure 1, thereby locking also said slide 8 and the handle or lever 2. Moreover, the interposition of the dog 40 by the lowering of the level of the liquid 30 also prevents the movement of the finger 23 and hence prevents the insertion of a coin through the coin slot 10. In Figure 4 there is shown a modified form of a float controlled lock embodying our invention, wherein there is provided a catch 43 pivotally mounted at 44 and having an outer arm 45. The outer arm 45 is connected through a rod or cord 46 to the outer end of the lever 47 which is pivotally mounted at 48 and has connected to the other end thereof, the rod 50 carried by the float 51. Thus, upon lowering the float 51 by a corresponding lowering of the level of the liquid, the catch 43 will engage the catch 12 thereby locking the same in the interlocking position shown in Figure 4, in a manner similar to that shown in Figure 1. Upon refilling the reservoir with a new supply of liquid the dog 40 and the catch 43 are again raised and the coin controlled apparatus rendered operative again.

Having thus described our invention, what we claim as new and desire to secure by Letters Patent is

1. In a device of the character stated, a coin support, actuating means to displace said coin support in a fixed path, a stationary serrated element and yieldable means intermediate said coin support and said stationary serrated element adapted normally to interlock with the serrations thereof, thereby to retain said coin support fixedly and adapted to be withdrawn from engagement with said serrations by the insertion of a coin into said coin support and an opposed serrated element for engagement by the coin.
2. In a device of the character stated, a slide, means to guide the same in a fixed path, a coin receiving aperture in said slide, a rack extending substantially parallel to the direction of movement of said slide, a spring catch carried by said slide in operative alignment with said rack adapted to engage the same and to interlock with the teeth thereof to lock the said slide against any movement thereof through the downward or operative stroke, means carried by said catch in operative alignment with the coin support adapted to be engaged and displaced by the coin when positioned in said support, thereby to withdraw said catch from locking engagement with said rack.
3. In a device of the character stated, a coin support, actuating means to displace said coin support in a fixed path, a stationary serrated element, yieldable means intermediate said coin support and said stationary serrated element adapted normally to interlock with the serrations thereof, thereby to retain said coin support fixedly and adapted to be withdrawn from engagement with said serrations by the insertion of a coin into said coin support and a second stationary serrated element adapted to interlock with the serrations of the coin support, thereby to prevent the return movement of said coin support until the same has reached the limit of its forward or operative movement.
4. In a device of the character stated, a slide, means to guide the same, a coin receiving aperture in said slide, means carried by said slide in alignment with said aperture to support a coin, a rack extending substantially parallel to the direction of movement of said slide, a spring catch carried by said slide in operative alignment with said rack adapted to engage the same and to interlock with the teeth thereof to lock the said slide against any movement thereof through the forward or operative stroke and means carried by said catch in operative alignment with the coin support adapted to be engaged and displaced by the coin when positioned in said support, thereby to withdraw said catch from locking engagement with said rack.
5. In a device of the character stated, a slide, means to guide the same, a coin receiving aperture in said slide, means carried by said slide in alignment with said aperture to support a coin, a rack extending substantially parallel to the direction of movement of said slide, a spring catch carried by said slide in operative alignment with said rack adapted to engage the same and to interlock with the teeth thereof to lock the said slide against any movement thereof through the downward or operative stroke, means carried by said catch in operative alignment with the coin support adapted to be engaged and displaced by the coin when positioned in said support, thereby to withdraw said catch from locking engagement with said rack.

movement of said slide in operative alignment with the edge of the coin positioned in said support, said means carried by said spring catch being adapted yieldably to urge the coin in said support, into interlocking engagement with said second rack, thereby to retain said slide against a return movement until the slide has been moved to the limit of its operative stroke and the coin 10 has passed the lower end of said second rack.

6. In a device of the character stated, a slide, means to guide the same in a fixed path, a coin receiving aperture in said slide, a coin support behind said aperture, a rack, 15 means carried by said slide for engaging, and interlocking with, the teeth of said rack, thereby to prevent the movement of the same, means actuated by a suitable coin forced into said coin receiving aperture to 20 withdraw said interlocking means from engagement with said rack and float control means adapted to lock said interlocking means against withdrawal by a coin from engagement with said rack.

7. In a device of the character stated, a 25 slide, means to guide the same, a coin receiving aperture in said slide, means carried by said slide in alignment with said aperture to support a coin, a rack extending substantially parallel to the direction of movement 30 of said slide, a spring catch carried by said slide in operative alignment with said rack adapted to engage the same and to interlock with the teeth thereof to lock the said slide against any movement thereof through the 35 forward or operative stroke, means carried by said catch in operative alignment with the coin support adapted to be engaged and displaced by the coin when positioned in said support, thereby to withdraw said catch from locking engagement with said rack and float actuated means adapted to lock said spring catch against withdrawal by a coin from 40 interlocking engagement with said rack and to prevent the insertion of a coin into said coin support.
